BENJAMIN C. PERKINS AND ROBERTS K. SKINNER, OF HARTFORD, CONNECTICUT.

INTERNAL-COMBUSTION ENGINE.

1,117,900.

Specification of Letters Patent. Patented Nov. 17, 1914.

Application filed February 16, 1914. Serial No. 818,918.

To all whom it may concern:

Be it known that we, BENJAMIN C. PERKINS and ROBERTS K. SKINNER, both citizens of the United States of America, and both 5 residing in the city of Hartford, county of Hartford, in the State of Connecticut, have invented certain new and useful Improvements in Internal-Combustion Engines, of which the following is a specification.

10 Our invention relates to improvements in internal combustion engines, the object being to so construct the engine as to increase its efficiency.

Our improvements are more particularly 15 applicable to gas engines of the two cycle type, and we have illustrated the improvements as applied to that type in the accompanying drawings.

In these drawings, Figure 1 is a vertical 20 section on the line 1—1, Fig. 2; Fig. 2 is a vertical section on the line 2—2, Fig. 1; Fig. 3 is a sectional plan view on the line 3—3, Fig. 1, but with the valve in a different position; Fig. 4 is a vertical section through 25 the valves on the line 4—4, Fig. 2; Fig. 5 is a vertical section on the line 5—5, Fig. 2; Fig. 6 is a sectional view showing throttle valves for the air and gas supplies.

The form of engine illustrated is of the 30 upright type, with two superposed cylinders B and D, the upper cylinder B of smaller diameter being the working cylinder, while the lower cylinder D of larger diameter is utilized for pumping the supplies of air and gas. The pistons A and C working in their 35 respective cylinders are attached to each other to move together, and may conveniently be described as constituting a double-diameter piston. Preferably the lower piston C is annular in form and works on its inner side on an inner stationary sleeve E, which is secured at its lower end to the outer casing F of the engine, just above the crank 40 chamber G. Air and gas supplies lead to the spaces above and below the piston C and the pump is a double acting pump to draw in and to compress separately charges of air and gas.

The engine illustrated in the drawings has 50 two working cylinders B, B', but it will be understood that the number of cylinders may be increased as occasion may require, or the essential features of our invention may be embodied in a single working cylinder engine.

For purposes of explanation, it will suf-

fice to describe a single cylinder, except where it may be necessary to explain the operation of the valves, in relation to the gas and air reservoirs. As shown, there is 5 a separate reservoir J (J¹) for the gas supply to each of the engine cylinders, Figs. 2 and 3, while the air reservoir H is shown as common to the two working cylinders. The separate admission of air and gas to 35 the pump, and also the flow of such air and gas to their respective reservoirs H and J (J¹) is preferably controlled by a valve K.

The admission of the separate charges of 40 compressed air and compressed gas separately and successively to the working cylinders from the reservoirs H, J, J¹ is controlled by a positively operated valve L, which in the drawing is shown as a rotary valve. These valves K and L may be geared 70 together as by gears 10, 11, Fig. 2, and driven from some moving part of the engine, or they may be otherwise positively actuated.

The gas inlet from the carburetor, is indicated at 12, leading through branched passages 13, 13¹, to ports 14, 14¹, which are controlled by the passages 15, 16 and 15¹, 16¹, in the rotary valve K. When the widest part 15 (15¹) of these passages is open to the 55 port 14 (14¹), as shown at the left of Fig. 2, the gas can flow through the valve to the port 17, (17¹) which lies in a different cross-sectional plane from the plane of the port 14 (14¹) but adjacent to the latter and leads 90 through passage 18 (18¹) to the interior of the pumping cylinder D below the piston C. This will be the position of the valve when the piston is rising, as in Fig. 1. When the piston is descending, the valve will be in such 95 position (shown at the right of Fig. 2), as to close the port 14¹ (14) and open the passage 18¹ (18) and port 17¹ (17) through the passages 16¹ (16) and 15¹ (15) in the valve and port 19¹ (19) to the gas reservoir 100 J¹ (J), so that the charge of gas which was drawn into the pumping cylinder during the rise of the piston will now on the down stroke of the piston be forced into the gas reservoir J¹ (J) and compressed therein.

The space on the upper side of the annular piston C is in like manner utilized to draw in and to compress the air separate from the gas. The air inlet is seen at 20, Fig. 2, and the admission to the pumping chamber 110 is controlled by the passages 25 (25¹) and 26 (26¹) in the valve K. In Fig. 2, the valve K

is shown in position to close the supply of air to the pumping chamber of the left hand cylinder of the engine but to open it through passages 25¹, 26¹ to the ports 27¹ and 28¹ to 5 the air pumping chamber of the right hand cylinder. At the same time the port 27 leading from the left hand engine is in communication through passage 25 with the port 29 leading to the air reservoir H. Thus on 10 the descent of the piston the air is admitted to and drawn into the pumping cylinder D above the piston C and when the piston begins to rise, the valve K will have turned to open the passage to permit this charge to be 15 forced into and compressed in the reservoir H.

There are shown two separate ports 30 and 31 (30¹ and 31¹) for the air and gas admissions from the reservoirs H, J, (J¹) to 20 the upper valve L. The preferred construction of this upper valve will be understood upon reference to Figs. 1 and 3. It is shown tubular with ports 32, 33, (32¹, 33¹) for the gas, and diagonal tubular passages 34 (34¹) 25 for the air. A single port 35 (35¹) leads from the valve to each cylinder. As will be understood by reference to Fig. 1, this port 35 (35¹) is some distance below the surface of the working piston A, when at the top of its 30 stroke, so as to be closed by the piston when the ignition takes place, and accordingly the valve L will not be mechanically affected by the blow of the explosion, nor directly subject to the heat of the ignition, until the 35 charge exploded has partly expanded.

In Fig. 3, the valve L is shown in such position that at the moment both air and gas are cut off from the working cylinder B at the left, while air is being admitted to the working cylinder B¹ on the right. The exhaust from the working cylinder is shown at O, Fig. 1, the inlet port for the air and gas 35 (35¹) being at a level considerably above that of the exhaust port. Any usual 40 or convenient form of spark plug is fixed in the opening P at the top of the working cylinder, Fig. 1. From the foregoing description, it will be observed that the air and gas reservoirs are in intermittent and alternate communication with the pumping cylinder and the working cylinder.

With the foregoing explanations, it will suffice to add the following general statement of the operation of the engine, reference being made for simplicity to the operation of but one of the two pairs of pistons and their cylinders and coöperating parts of the valves K and L:—On the upstroke of the piston, gas from the carbureter is 45 drawn into the lower pumping chamber by the piston C through the lower rotary valve K; on the return or downstroke of the piston, this charge of gas is forced from the lower pumping chamber into the gas storage reservoir J (J¹), and at the same down

stroke of the piston C air is drawn into the upper pumping chamber, and this charge of air is forced into the air storage reservoir H on the up stroke of the piston. From these storage reservoirs the air and gas are 50 admitted separately to each working cylinder by proper turning of the valve L, that is to say, when the working piston is at or near the bottom of its stroke and uncovering the exhaust port, the valve L will be in such 55 position as to admit a rush of air under pressure to the working cylinder through port 35 to scavenge the burnt gases out through the exhaust. About the time the piston, in rising again, has covered the exhaust port, the valve L will turn to close off the air supply, but leaving a volume of 60 fresh air in the cylinder, gas under pressure from the reservoir J (J¹) will then be admitted to the working cylinder to mix 65 with the charge of fresh air already there. About the time the pressure in the working cylinder approximately equals the pressure in the gas reservoir the valve L will close off the supply of gas to the cylinder. In 70 Fig. 1, this valve L is shown in position about to close the gas supply to the working cylinder. At the end of the compression stroke of the piston, the charge is ignited to give the working stroke to the piston, and 75 thereafter the cycle of operations will be 80 repeated.

Owing to the fact that the positively actuated valve means controlling the separate admission of the compressed air and gas to 85 the working cylinder, are outside the cylinder and apart from the piston itself, we have a better control over the operation than if the piston or cylinder was used as a part 90 of said valve means.

We provide the air storage reservoir H with a suitable valve h, to let off the air pressure when desired, as for example, when in starting it is desired to provide the working cylinder with a rich combustible mix- 100

ture for the first ignitions. The air and gas supply inlets may be provided with throttle valves, as indicated, for example, in Fig. 6, in which the air inlet is shown as provided with a valve 120 and the gas inlet with a valve 112, and the axes 105 of these two valves have arms 113 and 114, which may have an adjustable connection 116, so that the quantities and relative quantities of air and gas supplied may be regulated.

As will be seen on reference to Figs. 1, 3 and 5, we extend the water jacket around the housing or seating for the valve L and around the port 35 (35¹) leading from the valve to the working cylinder, so that the housing or seating may be kept at an approximately uniform temperature and so permit the valve to run freely in its seating 115 at all times. Also as shown in the 120

drawings, considerable portions of the rear walls of the air and gas reservoirs H, J and J¹ also constitute the outer walls of the waterjacketing of the working cylinders 5 and the valves, so that there is an interchange of heat and cooling between the working cylinder and incoming air and gas through the medium of the intervening waterjacket. This also aids in keeping the 10 valve L and its seating at an approximately uniform temperature, by the warming of the incoming supplies of air and gas and the cooling of the cylinder. This preliminary heating of the gas and air also makes their 15 mixture in the working cylinder more explosive.

We claim as our invention:—

1. An internal combustion engine, having a working cylinder, a pumping cylinder of larger diameter, connected pistons of correspondingly different diameters and separate reservoirs for the compressed gas and the air from the pump, in combination with positively actuated valve means outside the cylinder to control the separate admission of air and gas successively to the working cylinder from the reservoirs. 20
2. A multiple cylinder internal combustion engine, having a pumping cylinder united with each working cylinder, two diameter pistons for the connected pumping and working cylinders, separate reservoirs for the compressed gas and the air in communication with the pumps and the working cylinders, in combination with positively actuated valve means outside the cylinder to control the separate admission of air and gas successively to the working cylinder from the reservoirs. 25
3. An internal combustion engine, having a working cylinder, a pumping cylinder of larger diameter, and a double diameter piston therefor, in combination with positively actuated valve means outside the cylinder to control the separate admission of air and gas successively to the working cylinder and a common port for the air and gas from said valve means to the working cylinder. 30
4. An internal combustion engine, having a working cylinder, a pumping cylinder of large diameter, a double diameter piston therefor, the pumping piston being adapted to supply separate charges of air and gas, a storage reservoir for the gas and a positively actuated valve means outside the cylinder to control the admission of gas to the working cylinder from said reservoir in combination with positively actuated means 35 to control the separate admission of air to the working cylinder.
5. A multiple cylinder internal combustion engine, having working cylinders and pumping cylinders of larger diameter united 40 with the respective working cylinders, and

double diameter pistons for the working and pumping cylinders, the pumping means being adapted to separately supply air and gas charges, positively actuated valve means outside the cylinders to control the admission of gas to the working cylinders and gas storage accommodations outside said valve means, in combination with positively actuated means to control the separate admission of air to the working cylinders. 70

6. An internal combustion engine, having a working cylinder, a separate pumping cylinder of larger diameter, a double diameter piston therefor, the pumping piston being adapted to supply separate charges of air and gas, separate storage reservoirs for the compressed air and gas, and positively actuated valve means outside the cylinder to control the admission of gas to the working cylinder, in combination with positively actuated means to control the separate admission of air to the working cylinder. 75

7. An internal combustion engine, having a working cylinder and a piston, a double-acting pump, whose piston is attached to the working piston, a crank chamber independent of said pump, said pump piston being adapted to draw and compress air on one side and to draw and compress gas separately on the other side and positively actuated valve means outside the cylinder to control the admission of gas to the working cylinder, in combination with positively actuated means to control the separate admission of air to the working cylinder. 90

8. An internal combustion engine having a working cylinder and piston therefor, and means for pumping the air and gas supplies separately in combination with separate reservoirs for the compressed air and compressed gas, positively actuated valve means controlling the admission of air and gas to the pump and from the pump to the reservoirs and positively actuated valve means outside the cylinder to control the separate admission of air and gas from the reservoirs to the working cylinder. 100

9. An internal combustion engine, having a working cylinder and a pumping cylinder of larger diameter and united pistons for the respective cylinders in combination with separate reservoirs for air and gas from the pump, positively actuated valve means controlling the admission of air and gas to the pump and their admission from the latter to their respective reservoirs and other positively actuated valve means outside the cylinder to control the separate admission of air and gas from the reservoirs to the working cylinder. 115

10. An internal combustion engine, having a working cylinder and piston therefor, a pumping cylinder of larger diameter, a stationary internal sleeve within the pumping cylinder and a piston between the lat- 120

125

130

ter and the sleeve, constituting a double-acting pump, the two pistons being attached together, in combination with separate reservoirs for the air and gas, and positively actuated valve means outside the cylinder to control the separate admission of the air and the gas from the reservoirs to the working cylinder.

11. An internal combustion engine, having a working cylinder and piston therefor, a pumping cylinder of larger diameter, and a piston therefor connected to the working piston, and constituting a double-acting pump in combination with separate reservoirs for the air and the gas, and two rotary valves, one between the pump and the reservoirs and the other between the reservoirs and the working cylinder, and controlling the separate admission of compressed air and compressed gas to the working cylinder.

12. A multiple cylinder internal combustion engine, having working cylinders and united pumping cylinders and pistons for separately pumping air and gas supplies, crank chambers independent of said pumping means, separate reservoirs for the compressed gas and the air, valve means to control the admission of air and gas to the pump and from the pump to the reservoirs, and positively actuated means to control the admission of air to the working cylinders, in combination with positively actuated valve means outside the cylinder to control the separate admission of compressed gas to the working cylinders.

13. An internal combustion engine, having a working cylinder and pumping cylinder, a double diameter piston, separate air and gas reservoirs, valve means to control the admission of air and gas to the pump and from the pump to the separate reservoirs, positively actuated means to control the admission of air from the air reservoir to the working cylinder, in combination with positively actuated valve means outside the cylinder to control the separate admission of compressed gas to the working cylinder from the gas reservoir.

14. A multiple cylinder internal combustion engine, having working cylinders and a pumping cylinder of larger diameter united with each working cylinder, double diameter pistons and separate reservoirs for the air and the gas common to more than one cylinder in combination with positively actuated means to control the separate admission of air and gas to the working cylinders from the reservoirs.

15. An internal combustion engine, having a working cylinder, a pumping cylinder of larger diameter, a double diameter piston, separate reservoirs for the air and the gas, and positively actuated valve means to control the admission of air and gas from

the sources of supply to the pump and from the pump to the reservoirs, in combination with positively actuated means to control the separate admission to the working cylinder from the reservoirs.

16. An internal combustion engine, having a working cylinder, exhaust means therefor, a pumping cylinder of larger diameter for separately discharging air and gas to the working cylinder, a double diameter piston, and positively actuated valve means outside the cylinder to control the admission of gas to the working cylinder when its exhaust means is closed, in combination with positively actuated means to control the separate admission of air thereto when the exhaust means is open.

17. An internal combustion engine, having a working cylinder and piston therefor, and air and gas pumping means in combination with positively actuated valve means to control the separate admission of compressed air and gas to the cylinder and means for throttling the supply of air and gas to the pumping means.

18. An internal combustion engine, having a working cylinder and piston therefor, a pumping cylinder of larger diameter whose piston is united to the working cylinder piston and which separately discharges air and gas to the working cylinder, an exhaust port in the working cylinder opened and closed by the piston, and positively actuated means to control the admission of gas to the working cylinder through its walls when the exhaust is closed, in combination with positively actuated means to control the separate admission of air thereto when the exhaust is open.

19. An internal combustion engine, having a working cylinder and a piston therefor, a pumping cylinder and a piston therefor attached to the working piston for separately compressing the air and gas supplies, and separate reservoirs for the air and gas, in combination with positively actuated valve means to control the separate admission of gas and air to the working cylinder through its walls, the exhaust port of said working cylinder being opened and closed by its piston.

20. An internal combustion engine, having a working cylinder and a piston therefor, and a double acting pump of larger diameter whose piston is attached to the working piston to compress gas during the power stroke and air during the compression stroke of said working piston and separate reservoirs for the air and gas, in combination with valve means to control the admission from the pump to the reservoirs for the air and gas.

21. A multiple cylinder internal combustion engine, having working cylinders and double acting pumps of larger diameter,

- whose pistons are attached to the working cylinder pistons in combination with gas reservoir means, the pumps forcing the gas to the reservoir means during the power stroke of said working cylinders and compressing the air during the compression stroke of said working cylinder, and valve means to control the separate admission of air and gas to the latter.
22. An internal combustion engine, having a working cylinder, a pumping cylinder, a double diameter piston, and means for separately admitting air and gas to the working cylinder in combination with a gas reservoir, and a positively actuated valve with united passages in said valve to control the admission of gas to the pump, and its passage therefrom to the reservoir.
23. An internal combustion engine, having a working cylinder, a pumping cylinder, and united pistons therefor, means for separately admitting air and gas from the pumping cylinder to the working cylinder, a valve housing in communication with the pumping chamber, positively actuated valve means in the housing, and united passages in said valve means to control the admission of air to the pump and its discharge therefrom through the same port in the housing.
24. A multiple cylinder engine, having working cylinders and two pumping cylinders, a common air supply, and an air reservoir common to the two pumps, in combination with a positively actuated valve to control supply of air to the pumps, and its discharge therefrom to the reservoir, said valve having passages opening to a common port leading to the source of supply and also opening to a common port leading to the air reservoir.
25. An internal combustion engine, having a working cylinder, an air pump and a gas pump, means for separately admitting air and gas to the working cylinder, a rotary valve having a single passage in intermittent communication with three ports in the housing, one port leading to the source of supply, a second leading to a chamber in intermittent communication with the working cylinder, the third leading to a pump and communicating with the valve in a different cross-sectional plane from that of the other ports.
26. An internal combustion engine having a working cylinder, a pumping cylinder of larger diameter, a double diameter piston operating in said cylinders, separate reservoirs for air and gas from the pump, positively actuated valve means to control the separate admission of air and gas through a port to the working cylinder, said working cylinder, valve and port being water-jacketed, part of the walls of the water jacket constituting also part of the walls of the reservoirs, for the purpose described.
27. An internal combustion engine, having a working cylinder, a pumping cylinder of larger diameter, a double diameter piston, and reservoirs for the air and gas, in combination with means outside said reservoirs and said working cylinder and associated therewith as a medium to impart a portion of the heat of combustion to the contents of said reservoirs and to cool said working cylinder.
28. An internal combustion engine having a working cylinder and a piston therefor, and a double-acting pump of larger diameter whose piston is attached to the working piston, separate ports for air and gas opening to the pump chamber on opposite sides of the piston and positively actuated valve means to control the admission and discharge of air and gas respectively through said separate ports in the pump.
29. An internal combustion engine, having a working cylinder and air and gas reservoirs with a water jacket around the working cylinder, part of the walls of the water jacket constituting also part of the walls of the reservoirs, for the purpose described.
30. An internal combustion engine, having a working cylinder and piston, a pumping cylinder of larger diameter, and an annular piston united with the working cylinder piston, in combination with a fixed sleeve over which the annular piston works, forming two pumping chambers, one for the air and the other for the gas, separate reservoirs for the air and gas, and positively actuated valve means to control the separate admission of air and gas to the working cylinder from the reservoirs.
31. An internal combustion engine, having a working cylinder and piston, a pumping cylinder of larger diameter and an annular piston united with the working cylinder piston in combination with a fixed sleeve over which the annular piston works, forming two pumping chambers, one for the air and the other for the gas, separate reservoirs for the air and gas, valve means between the supplies and the pumping chambers and between the latter and the reservoirs and positively actuated valve means to control the separate admission of air and gas to the working cylinder from the reservoirs.
32. An internal combustion engine, having a working cylinder, a pumping cylinder of larger diameter, a two-diameter piston therefor, and separate reservoirs for the air and gas, a rotary valve means controlling the admission of air and gas to the pumping chambers and from the latter to the separate reservoirs, and a separate rotary valve controlling the separate admission of air and gas to the working cylinder from the reservoirs.
33. An internal combustion engine, hav-

ing a working cylinder, and a pumping cylinder and pistons therefor in combination with air and gas reservoirs and controlling valves, the air reservoir having a manually controlled relief valve for temporarily lowering the pressure in the air reservoir on the starting of the engine.

In testimony whereof we have signed our

names to this specification, in the presence of two subscribing witnesses.
